US00D998169S

(12) **United States Design Patent** (10) **Patent No.:** **US D998,169 S**
Sanchez et al. (45) **Date of Patent:** **** Sep. 5, 2023**

(54) **PIPETTE**(71) Applicant: **Gilson, Inc.**, Madison, WI (US)(72) Inventors: **Marc Sanchez**, Paris (FR); **Tristan Berto**, Madison, WI (US)(73) Assignee: **GILSON, INC.**, Middleton, WI (US)(***) Term: **15 Years**(21) Appl. No.: **29/854,206**(22) Filed: **Sep. 22, 2022****Related U.S. Application Data**

(60) Division of application No. 29/728,443, filed on Mar. 18, 2020, now Pat. No. Des. 969,340, which is a division of application No. 29/646,251, filed on May 2, 2018, now Pat. No. Des. 879,318, which is a continuation of application No. 29/580,717, filed on Oct. 12, 2016, now abandoned, which is a division of application No. 29/479,141, filed on Jan. 13, 2014, now Pat. No. Des. 772,426.
